CLAIM

The ornamental design for a corner mount passive infrared motion detector, as shown and described.

DESCRIPTION

FIG. 1 is a perspective view of the top front corner mount passive infrared motion detector of the invention;
FIG. 2 is an enlarged front elevational view of the corner mount infrared detector of the invention;
FIG. 3 is a rear view of the corner mount passive infrared motion detector;
FIG. 4 is a bottom view of the corner mount passive infrared motion detector; and,
FIG. 5 is a left side view of the corner mount passive infrared motion detector of the invention; the right side view is a mirror image of the left side view.
